Inventor,
G. W. Billings

UNITED STATES PATENT OFFICE.

G. W. BILLINGS, OF ST. PAUL, MINNESOTA.

IMPROVEMENT IN ROTARY FORCING-PUMPS.

Specification forming part of Letters Patent No. 36,888, dated November 11, 1862.

To all whom it may concern:

Be it known that I, G. W. BILLINGS, of St. Paul, in the county of Ramsey, in the State of Minnesota, have invented new and useful Improvements in Rotary Forcing-Pumps; and I do hereby declare that the following is a full, clear, and exact description of the construction and operation of the same, reference being had to the annexed drawings, making a part of this specification, in which—

Figures 1, 2, and 3 are several views of a rotary forcing-pump with said improvements attached, and Figs. 4 and 5 are views of such improvements detached.

The construction and operation of the same are as follows: A and A' is a stationary hollow cylinder.

B and B' is an eccentric cam-wheel revolving within the cylinder A and A' by means of the chain G.

D and d is a follower attached to the cam-wheel B and to the cut-off F and F' at E.

G and G' is a stop attached to the foot of the cut-off F and F' and forming a part of it.

H and I are ports opening from the cylinder A', the one at H opening into the tube J and J' and the one at I opening into the external water.

The revolution of the cam-wheel B' forcibly ejects the fluid through the port H.

When desirable to force the fluid through a small pipe leading directly from the axis L of the cam-wheel, instead of through the tube J

and the port H, a port, K, in the side of the cam-wheel, communicating with a receiver in the side of the wheel, running into the axis, as seen in Fig. 3, will be necessary, and in this case the stop G' at the foot of the cut-off F' acts as a valve to close the port I when the port K is brought opposite to it in the revolution of the cam, thus preventing the escape of the fluid and saving power.

The cam-wheel is intended to be constructed and operated as represented in Fig. 3, or as represented in Fig. 4, where it is formed by the combination of two segments of the single wheel, thus forming a kind of double-eccentric cam-wheel.

Fig. 5 is a view of the cam-wheel, cylinder, cut-off, driving-wheel, and follower.

What I claim as my invention, and desire to secure by Letters Patent, is—

1. The eccentric revolving cam-wheel B B', in combination with the stationary cylinder A A', and with the adjustable cut-off F F', constructed and operating as represented in Fig. 3.

2. The stop G G', in combination with the cut-off F F' and the eccentric and connecting-rod D d, and cam-wheel B B', all operating in the manner and for the purposes substantially as set forth.

G. W. BILLINGS. [L. S.]
